UNITED STATES PATENT OFFICE.

CORA C. MEYERS, OF NEW YORK, N. Y.

DESIGN FOR A COMBINED ELECTROLIER AND COVER.

Application filed April 30, 1926. Serial No. 17,518. Term of patent 7 years.

To all whom it may concern:

Be it known that I, CORA C. MEYERS, a citizen of the United States, residing at No. 850 Ninth Avenue, New York city, in the county and State of New York, have invented a new, original, and ornamental Design for a Combined Electrolier and Cover, of which the following is a specification, reference being had to the accompanying drawing, forming part thereof.

The drawing is a front view of a female figure, dressed in a fabric material with a superimposed shade.

I claim:

The ornamental design for a combined electrolier and cover, as shown and described.

CORA C. MEYERS.
